UNITED STATES PATENT OFFICE.

ZABDIEL A. WILLARD, OF BROOKLINE, MASSACHUSETTS, ASSIGNOR TO CAROLINE WEST, OF BROOKLINE, MASSACHUSETTS.

APPARATUS FOR GENERATING COMBUSTIBLE VAPOR.

1,169,706.

Specification of Letters Patent. Patented Jan. 25, 1916.

Application filed August 31, 1912. Serial No. 718,049.

To all whom it may concern:

Be it known that I, ZABDIEL A. WILLARD, a citizen of the United States, and resident of Brookline, in the county of Norfolk and State of Massachusetts, have invented certain new and useful Improvements in Apparatus for Generating Combustible Vapor, of which the following is a specification.

This invention relates to apparatus for generating and burning gases. I use a mixture of hydrocarbon and steam and pass the mixture thereof through a retort in which the hydrocarbon and steam are decomposed by heat, and burn the gases which are formed in the retort, directing a flame of said gases against the retort to effect the decomposing operation.

I am aware that this process is not broadly new; but my invention includes a new combination and arrangement of parts of the apparatus whereby I obtain an improved result.

So far as I am aware, hydrocarbon vapor has never been fed by pressure equal to that of the live steam which is mixed with the vapor; but according to my invention, the pressures of the hydrocarbon vapor and live steam are equal, and my apparatus whereby this equalization of pressure is maintained enables me to use either a hydrocarbon vapor or liquid hydrocarbon as the substance which is mixed with the steam to supply the mixture which is decomposed to supply the combustible gases.

The accompanying drawing illustrates, somewhat conventionally, an apparatus embodying my invention. The drawing represents, in vertical section, the gas-producing and gas-burning apparatus in co-operative relation to a steam generator.

The same reference characters indicate the same parts wherever they occur.

The steam generator, indicated at 10, is broken away in two places and shortened from front to rear, solely for the purpose of saving space on the drawing. This shortening of the generator gives the combined apparatus an abnormal appearance; but if it is borne in mind that the steam generator should be about twice as long as it appears

to be, the proportions would be approximately correct.

The combustion chamber of the generator comprises a lower trunk 11, an upwardly extending trunk 12, a short upper trunk 13, 55 and a plurality of fire tubes 14 which constitute continuations of the trunk 13 and which discharge the products of combustion into the outlet flue 15. The left-hand end of the trunk 11 is open to receive the burner 60 hereinafter described.

16 is a draft regulator arranged in the outlet flue 15.

My apparatus for generating combustible gases comprises a source of steam under 65 pressure, a source of hydrocarbon oil under the same pressure as the steam, means for mixing streams of hydrocarbon and steam, and means for decomposing the mixture.

I have indicated at 5 a relatively small 70 steam generator whose purpose is to supply the necessary steam for starting the operation. This auxiliary generator 5 will, in practice, be used only until there is a sufficient pressure of steam in the main generator 75 10.

A steam supply pipe 6 extends from the starting generator 5 and has a shut-off valve 7. Pipe 6 connects with a steam pipe 23 which has branches 24 and 25. Branch 24 80 extends into a pressure-sustaining tank or reservoir 20 into which hydrocarbon oil is supplied by any suitable means, such as a pipe 21. A valve in said pipe is indicated at 21^x. 85

The oil reservoir is provided with a sight gage 22 whereby the desired quantity of oil may be determined. The horizontal broken line about midway between the top and bottom of this sight gage indicates the desired 90 level of oil. The delivery end of the steam pipe 24 is submerged in the oil and is indicated at 26. The pressure in the reservoir 20 is equal to the pressure in the steam generator. 95

The retort is indicated at 37. I may feed liquid hydrocarbon, or hydrocarbon vapor, or a combination of both, as desired, from the reservoir 20 to the retort. A supply pipe 30 connects the reservoir with the re- 100

tort, the receiving end of said pipe being submerged in the oil in the reservoir. This pipe has a valve 46, which, when open, enables liquid hydrocarbon to flow to the retort. The pipe 30 has a branch 29 for conducting hydrocarbon vapor from the reservoir 20 to the retort, the receiving end of said branch being above the level of oil in the reservoir. This branch is controlled by a valve 44. It is apparent that if valve 44 be open and valve 46 be closed, only hydrocarbon vapor will flow to the retort, while if valve 44 be closed and valve 46 be open, only liquid hydrocarbon will flow to the retort. If desired, both valves may be opened at the same time.

In order to vaporize the hydrocarbon oil in the reservoir 20, I provide a steam coil 27 which is a continuation of the steam pipe 20 25. The outlet of coil 27 is indicated at 28.

Steam is introduced into the fuel feed pipe 30 by a steam pipe 33 which receives steam from the pipe 23. The admission of steam to the pipe 30 is controlled by a valve 25 45. A check valve is inserted in the pipe 30 at 51, said check valve opening toward the retort.

The gases which are formed in the retort are conducted through a pipe 38 to a burner. 30 I have shown a burner which is specially designed for this purpose, although it is to be understood that any suitable burner may be used. The burner as shown comprises a shell or casing 39 and a core 40. The supply pipe 38 delivers the gases into two branch pipes 41 whereby the gases are admitted into the shell 39 at opposite sides of the core and are sufficiently distributed in the chamber within the shell. The gases are 35 emitted from the shell through an orifice 32. The core 40 is adjustable toward and from this orifice, and the end toward the orifice is tapered. The surrounding portion of the shell 39 is likewise tapered, whereby the 40 flame is given a conical form and caused to envelop the retort and fill the trunk 11. A screw 40^x is provided for adjusting the core 45 toward and from the orifice 32.

The apparatus is operated as follows:— 50 Having started combustion in the generator 5 and generated sufficient steam therein for vaporizing the oil in the reservoir 20, the valve 44 may be opened to permit hydrocarbon vapor to be forced by the steam pressure 55 behind it through the retort and thence through the orifice 32 of the burner, where it will be ignited. The retort is thus heated, and increases the heating properties of the gases which are passing through it. When 60 the retort has been heated to a sufficient degree, live steam may be admitted into the pipe 30 by opening the valve 45, steam and hydrocarbon vapor under equal pressure being thus mixed prior to passing through the

retort. The mixture is decomposed while passing through the retort, and the gases formed increase the intensity of the heat given off by the flame. As the retort becomes hotter the supply of hydrocarbon vapor may be decreased and the supply of steam increased by adjusting the valves 44 and 45 respectively. When sufficient steam pressure has been generated in the generator 10, such steam may be used instead of that from the starting generator 5, by opening 75 the valve 23^x which enables steam to pass from the generator 10 through the steam pipe 23 to feed the branches 24, 25 and 33 hereinbefore described. When the hydrocarbon oil in the reservoir 20 has been vaporized to such extent that it can no longer supply sufficient vapor, it may be conducted in its liquid state to the retort by opening the valve 46, being mixed in passing, with steam from the pipe 33. So long as there is 80 any vapor remaining in the reservoir 20, the valve 44 may be left open; but when feeding liquid hydrocarbon through the pipe 30 it is immaterial whether the valve 44 be open or closed, because the pressure in the reservoir 20 is at all times equal to the pressure of the steam which is admitted into the pipe 30 from the pipe 33.

In order to keep the hydrocarbon vapor heated sufficiently while passing from the reservoir 20 to the retort, I inclose a substantial part of the pipe 30 in a steam jacket formed by a casing 31. Steam is admitted into this jacket through a pipe 132 which has a valve 35, and the exhaust is conducted 100 away by a pipe 34 which has a valve 36. If it is desired to induce a draft through the combustion chamber, I may admit steam into the outlet flue 15 from an ejector pipe 52 which has a valve 53.

The thick, heavy grease which results from vaporizing the hydrocarbon oil in the reservoir 20 collects at the bottom of the reservoir, and I have provided a discharge pipe 49 therefor, said pipe having a valve 50. 110 The reservoir 20 is provided with a lower sight gage whereby the quantity of such heavy grease may be observed. Water collects in small quantities as the result of condensation of steam which is emitted from 115 the pipe 24 in the oil reservoir. Such water, of course, collects at the bottom of the reservoir and may be drawn off through the pipe 49. The reservoir 20 is provided with a pressure gage 47 by which the attendant 120 may be informed when sufficient initial steam pressure has been generated for starting.

I claim:

An apparatus for the purpose specified, 125 comprising a closed, pressure-sustaining, oil-fuel reservoir, a burner, a fuel-feed pipe arranged to conduct oil and oil vapor from

said reservoir to said burner, said pipe having two fuel-receiving branches, the receiving end of one of said branches being below the oil level in said reservoir, and the receiving end of the other one of said branches being above said oil level, said branches having valves to regulate the flow of oil and vapor respectively, a source of steam under pressure, a steam pipe arranged to conduct steam from said source into said fuel feed

5 pipe between said retort and the junction of said branches, and a steam pipe arranged to conduct steam from said source into the oil in said reservoir.

In testimony whereof I have affixed my 15
signature, in presence of two witnesses.

ZABDIEL A. WILLARD.
